UNITED STATES PATENT OFFICE

CHARLES E. ROGERS, OF DETROIT, MICHIGAN

VACUUM PAN

Application filed June 13, 1925. Serial No. 36,856.

This invention relates to vacuum pans for condensation of fluids containing solids, for instance milk, and is a substitute for my former application Serial No. 484,617, filed July 5 14, 1921.

The object of the invention is to provide an apparatus of the character stated having an increased efficiency over previous known apparatus for the same purpose in that the 10 output per unit of heat applied is increased and "foaming" is practically eliminated. In the majority of previous known apparatus the usual vacuum pans for condensation of milk or the like have an upper portion of a reduced diameter and a condenser on the exterior of the pan.

Within my improved vacuum pan and extending diametrically thereacross at the top, I provide a condenser of comparatively narrow 20 width, the condenser being provided with means arranged diametrically across the pan above the trough for discharging water in fine streams into the trough. Vapor is permitted to rise upon both sides of the 25 trough to contact the streams of water.

A further feature of the invention is also involved in the construction of a pan of substantially uniform diameter to a point practically level with the point of discharge of the 30 condensing water into the pan.

By the general construction stated—that is, the forming of the pan of the same diameter up to the point of entrance of condensing fluid—the vapors pass from the apparatus 35 more readily and the velocity of movement and pressure during evaporation is reduced. These various objects and the several novel features are hereinafter more fully described, and the preferred form of construction of a vacuum pan embodying my invention is shown in the accompanying drawings in which—

Fig. 1 is a vertical section of my improved 40 vacuum pan.

Fig. 2 is a transverse section taken on line 2—2 of Fig. 1.

Fig. 3 is a section in detail on an enlarged 45 scale taken on line 3—3 of Fig. 1.

Fig. 4 is a section taken on line 4—4 of Fig.

1 showing the arrangement of the apertures for discharge of the water into the pan.

The pan as shown consists of a cylindrical shell 1 which may, if desired, be formed of several flanged sections and provided with a top cover 2 and a bottom 3. The seams between the several sections of the cylinder and top and bottom members are necessarily made air tight. A manhole of any approved type indicated at 4 is utilized near the upper 55 end of the cylindrical member which is to be understood as being provided with the usual peep glass. A thermometer of the usual type is also provided as shown in dotted lines at 5 and the usual milk inlet as shown in dotted lines at 6 and the butter cup indicated by dotted lines at 7. In the lower part of the pan are positioned the heating coils 8 which may be of any approved type and are here shown as being made up of separate sections 60 indicated by the inlets 9, 10 and 11. As will be understood from Fig. 2 the outlets are at one side of the inlet coils, which outlets are indicated at 12 and an outlet for another coil at 13. However, as before stated, any type 65 of heating coil may be used as may be found desirable so far as this invention is concerned. A heating coil in sections as here shown is desirable permitting the device to be economically operated with different 70 quantities of milk—that is, with a small quantity of milk the lower coil only with the inlet 11 may be utilized, which coil is provided with an outlet 14 extending through the bottom of the tank. If a greater quantity 75 of milk is used the next succeeding coil may be heated etc., as will be readily understood.

Preferably, although not of necessity, the pan is provided with an upwardly curved hemi-spherical bottom portion 15. With 80 heat applied to the coils, the milk adjacent thereto is heated and an upward flow thereof is occasioned circularly about the center which is not so highly heated. The cooler central space provides for practically unrestricted downward flow of cooler fluid with an upward current of the heated fluid in circular form. The upwardly extending hemi-spherical portion 15 tends to cause this downward current to spread beneath the lower 85 90 95 100

heating coils at the bottom of the ascending current.

Efficiency is also increased by making the pan of the same diameter throughout its height thereby avoiding necessity of increasing the velocity of flow of vapor through the upper portion as with the former types in which the upper part was usually of reduced diameter. This arrangement also permits an increase in the size and structure of the condenser which preferably consists of the U shaped trough 16 extending diametrically across the upper end of the pan as will be understood from Figs. 1 and 3. This trough member is provided with an outlet 17 to which the usual pump is attached to reduce the pressure in the pan and the outside wall of this trough is insulated as indicated at 16^a by any preferred type of heat insulating material, the purpose of which is to prevent condensation of the vapors coming in contact with the exterior of the cold trough 16. A water inlet 18 is provided in the top of the pan and a chamber 19 is provided therebelow having a multiple series of apertures 20 through which water is discharged into the trough 16 which falls thereinto in fine streams. The trough is spaced a distance below the water chamber 19 as will be observed more particularly in Fig. 3 and the vapors rising to the top of the pan pass into the streams of cold water which cause the same to condense and this water and condensed vapor pass out through the outlet 17. The trough 16 is of greater width than the water chamber 19 as will be understood from Fig. 3 preventing possibility of any water passing into the pan proper and the vapor may rise and pass into the streams of water from both sides of the trough permitting a greater volume of vapor per unit of time to come in contact with the cold condensing water than is possible with former constructions. With the former types of vacuum pans having the constricted upper end, a greater expenditure of effort was required as compared with the type here shown to maintain the vacuum due to the necessity of increasing the velocity of the flow of vapor at the restricted end and the tendency of such restricted end to increase the pressure in the pan. With the cylindrical pan of uniform diameter as here shown, the desired degree of vacuum is more readily maintained and without variation in pressure. Also an increased rapidity of evaporation is secured, due to the method of applying the heat. As heretofore stated the vapors may move more slowly than with the former type and still a greater rapidity of condensation is secured due to the area of the vapor permitted to contact with the cold streams of water. The structure of the condenser and the positioning of it diametrically across the shell at the upper end permit the vapor to rise to contact with the

condensing water on both sides of the condenser for the full length thereof. This equally distributes the steam or vapor relative to the water streams and it is possible to condense the vapor with a less volume of water thereby effecting a material saving in the cost of operation. By forming the pan of uniform diameter throughout its height the velocity of the vapor is not increased as it passes to the condenser and therefore the pressure during evaporation is not increased.

With the previous constructed types of vacuum pans heretofore mentioned and with the type of pan shown in the U. S. patent to C. T. Rogers, No. 795,650 there is a tendency for the non-condensable vapors to accumulate in the top of the pan and thus prevent the condensable vapors properly coming in contact with the condensing water and passing from the pan. In my improved form of water chamber I preferably form the bottom 20^a in a slightly curved form as shown in Fig. 3. On the outer longitudinal sides of the water chamber I provide a series of rows of apertures quite closely spaced and between these two marginal rows other rows of apertures are provided in which both the rows and apertures are spaced farther apart than is the case with the marginal rows. The vapors, in passing up in the direction of the arrows shown in Fig. 3 over the trough, pass into the streams of the condensing water. It will be noted that there is a large area of water with which the vapors may come in contact in passing into the trough. The arcuate form is preferred to cause a distribution in the water chamber 19 to each of the longitudinal sides to insure the maximum flow at these points but water is discharged also at the center of the water chamber to prevent an accumulation of noncondensable gases between the marginal rows of streams of water. These central streams drive any noncondensable gases downward into the trough to discharge from the pan. If the streams were arranged to fall in a circle or some similar form within which there is an area that may become filled with noncondensable gases, the presence of such gases within the outer wall of the water streams prevents movement of the condensable vapors into the streams and the noncondensable gases in such previous gases accumulate until there is sufficient pressure to force the same over and out through the outlet. This of course is practically instantaneous and is very detrimental in that the vacuum is increased and the heat leaves the fluid so rapidly as to cause it to foam, in fact to rise to the top of the pan and pass out through the outlet after which period such previous type of pan may again function properly for a time until the noncondensable gases have again accumulated. By my improved construction in which the pan

is of uniform diameter to a point level with the point of entrance of the vapor streams there is no increased velocity of the vapors in the upper part of the pan as is the case with the constricted type heretofore mentioned but in fact a slower movement of vapor is secured although greater in volume. By arranging the condenser extending diametrically across the pan with flow of vapor to both sides of the body of the streams the condensation is rapid due to the area of vapor in contact with the water.

These features coupled with the increased efficiency of the heating apparatus result in a more highly efficient apparatus than has heretofore been known in this art and the cost of condensing fluids is reduced while also the cost of manufacture of the pan as compared with that of the heretofore used restricted type is also materially reduced.

What I claim and desire to secure by Letters Patent of the United States is—

1. A vacuum pan, a shell of substantially uniform diameter throughout its height, a condenser within the shell at the top, said condenser consisting of an open trough shaped member near the top extending diametrically thereacross and having an outlet to the exterior of the shell, a water chamber thereabove less in width than the trough, the bottom wall thereof having a series of rows of apertures throughout its length and width for discharging the water into the trough, the marginal rows of the apertures being greater in number than the rows discharging centrally over the trough.

2. In a vacuum pan, a shell of substantially uniform diameter throughout its height, a cover plate therefor, a water chamber on the under side of the cover plate, the lower bottom wall of which is substantially in alignment with the end of the shell, and the bottom wall being perforated practically throughout its length and width providing apertures through which water may be discharged, the chamber being narrow in width extending diametrically across the top of the shell, a trough shaped member below the said top of the shell and beneath the water chamber, the said trough being greater in width than the water chamber and the arrangement permitting vapors to flow upwardly and inwardly over the trough to contact with the water streams, and an outlet for the trough leading to the exterior of the shell.

3. In a vacuum pan, a shell of substantially uniform diameter throughout its height, condensing means in the upper part of the shell, said condensing means comprising a trough shaped member of comparatively narrow width extending diametrically across the shell and provided with an outlet to the exterior at one end of the trough, a water chamber above the trough the bottom of which

is less in width than the trough and higher at the center than at the marginal edges, the said bottom throughout its length and width being provided with a series of apertures extending longitudinally thereof at each edge and other rows of apertures between the said marginal rows spaced a greater distance apart than the marginal rows.

4. In a vacuum pan, a shell of substantially uniform diameter throughout its height, a condenser near the top consisting of an open trough shaped member extending diametrically across the said top and having an outlet to the exterior of the shell, means positioned above the trough adapted to discharge water in fine streams throughout an area approximately equal to the length of the trough and less than the width thereof providing for a flow of gases into the trough from both sides, and preventing an accumulation of gases in the shell above the trough.

In testimony whereof, I sign this specification.

CHARLES E. ROGERS.
